UNITED STATES PATENT OFFICE.

WILLIAM W. TURNER, OF CHICAGO, ILLINOIS.

DESIGN FOR A ROOF-PLATE.

SPECIFICATION forming part of Design No. 26,201, dated October 20, 1896.

Application filed February 23, 1895. Serial No. 539,490. Term of patent 14 years.

To all whom it may concern:

Be it known that I, WILLIAM W. TURNER, a citizen of the United States, residing at Chicago, county of Cook, State of Illinois, have 5 invented and produced a certain new and original Design for Roof-Plates or Shingles, (Case D;) and I declare the following to be a full, clear, and exact description of the design, such as will enable others skilled in the 10 art to which it pertains to make and use the same, reference being had to the accompanying drawing, which forms a part of this specification.

In the drawing the figure is a perspective 15 view of my plate.

In carrying out the invention, A represents a flat panel of the roof-plate; B B', convex portions turned up from the flat panel A.

C is a curled-up edge of the convex portion B', having its convex face upward. ²⁰

It will be seen that by the above configuration I have produced a roof-plate which when placed upon the roof with others of the same shape will produce an effect of a flat portion, a rounded portion, and a rounded bead on ²⁵ the rounded portion.

What I claim is—

The design for a roof-plate, substantially as herein shown and described.

In testimony whereof I sign this specification in the presence of two witnesses. ³⁰

WILLIAM W. TURNER.

Witnesses:

W. H. CHAMBERLIN,
FLORENCE KING.
